UNITED STATES PATENT OFFICE.

LANCELOT RYAN, OF ST. LOUIS, MISSOURI.

RAILWAY-CROSSING.

1,304,207.

Specification of Letters Patent. Patented May 20, 1919.

Substitute for application Serial No. 49,941, filed September 10, 1915. This application filed March 29, 1919. Serial No. 286,147.

To all whom it may concern:

Be it known that I, LANCELOT RYAN, a citizen of the United States, and a resident of the city of St. Louis, in the State of Missouri, have invented a new and Improved Railway-Crossing, of which the following is a full, clear, and exact description.

My invention relates to railway crossings, particularly crossings of street railways, and has for its prime object the purpose of reducing the pounding and jar incident to the use of crossings as ordinarily constructed.

In the ordinary crossing, the bumping or pounding is caused by the car wheel jumping across the car groove formed in the crossing track for the flange of a wheel traveling on the other track. In my invention I provide an elevation at the distant side of the flange groove and a bevel or incline leading to said elevation, the arrangement being such that before the tread of a crossing wheel leaves the rail at one side of a groove, the tread of the wheel at 20 a forward point thereon will contact with the incline leading to the elevated tread surface of the track. Thus, the pounding of the car wheel against the track surface at the opposite side of the groove is reduced to a minimum.

The invention will be particularly explained in the specific description following:

Reference is had to the accompanying drawings forming part of this specification, in which similar characters of reference indicate corresponding parts in all the views, and in which:

Figure 1 is a plan view of a railway crossing embodying my invention;

Fig. 2 is a detail cross-section of a rail, giving the preferred form of the rails at the crossing;

Fig. 3 is a longitudinal vertical section 45 on the line 3-3 of Fig. 1; and

Fig. 4 is a perspective view of the crossing, the tread members of the rails being omitted except at one corner of the crossing.

In constructing a practical embodiment of my invention, the rails at the crossing are preferably composed of a base section 10 presenting flanges and a web, and said base section receives a tread section 11 having

spaced depending flanges 12 receiving between them the web 10 of the base section, the connection being completed by suitable bolts 13 and nuts 14. Thus the crossing will be composed of a permanent base presenting flanges and vertical webs, together with removable quarter sections, see Fig. 2, and the lower right hand corner of the crossing, Fig. 4. The construction permits of the renewal of a particular quarter section when worn, without renewing the base structure, and is applicable to crossings generally of steam railways and street railways. The crossing, in the tread surfaces of the rails, will present grooves 15 for the flanges of a car wheel.

I have designated the rails of one track generally by the letter A and the crossing tracks by the letter B, and in Fig. 3 have indicated car wheels C. Referring particularly to Figs. 1 and 3, it is to be assumed in these figures that cars travel in the direction of the arrows on the tread surfaces a , b , of the tracks (Fig. 1) and in the direction of the arrow in Fig. 3. The tread surfaces a are at the regular height of the tread surfaces of the rails generally throughout the tracks, and I provide in that rail at the left of the track, that is, at the lower side of Fig. 1, at the opposite side of the first groove 15 to be crossed, a rise or incline a^1 which leads to an elevated portion of the tread surface. At the right of Fig. 3 it will be seen that before the wheel C leaves the regular level a , a forward part of the tread surface of the wheel C will have contacted with the incline a^1 . Hence there will be a minimum pounding of the wheel in passing from the surface a to the incline a^1 . The track will gradually lower from the elevated portion adjacent to the incline a^1 , as indicated in Fig. 3 until the regular level a is again reached adjacent to the next groove 15 to be crossed, and at the opposite side from said next groove a second rise or incline a^2 is formed.

Adjacent to the incline a^1 and at right angles thereto I form an incline b^1 , at the opposite side of a groove 15 from the tread surface b at the regular level, so that a car wheel traveling along the rail B will strike the incline b^1 in the same manner as described with reference to the surfaces a^1 . Since the surfaces a , b , leading to the in-

clines a^1, b^1 are on the same level, the surface incline b^1 will start and finish at elevations corresponding to the start and terminal of the incline a^1 . At the lower left hand corner of Fig. 1, however, it is to be observed that a wheel in crossing from b to the incline b^2 at the opposite side of a groove 15, will first travel over the incline a^2 in the rail A and hence will travel from an elevated portion of the rail A to the inclination b^2 . Therefore, the incline b^2 starts at an elevation corresponding with the highest portion of the incline a^2 and rises to a higher elevation in the track B. Thus the incline a^2 rises from the regular level a and the incline b^2 rises to a higher elevation than the incline a^2 . Assuming that in practice there will be a rise of, for example, one-tenth of an inch at the incline a^2 and a further rise of one-tenth of an inch at the incline b^2 there will be a total rise of two-tenths from the regular track level at the incline b^2 .

Referring now to the upper right hand corner of Fig. 1, it will be seen that the conditions are similar to the lower left hand corner. Thus a wheel traveling from the surface b to the incline b^3 will be carried upwardly from said incline. Hence the incline a^3 in the rail A, adjacent to the incline b^3 will rise relatively to said incline b^3 , the relation between b^3 and a^3 being the same as with respect to the inclines a^2, b^2 . In the upper left hand corner of Fig. 1, it will be seen that conditions are such that the two inclines a^4, b^4 will correspond, since no elevation is crossed by a wheel on either track A, B, in passing to either incline a^4, b^4 , these having the same elevation above the regular track level. The inclines a^4, b^4 meet in a miter line. In all

cases it will be seen that the incline is at the far side of a groove to be crossed by the tread of a wheel and in all cases the incline will rise relatively to the level at the near side of the groove. 45

Having thus described my invention, what I claim as new and desire to secure by Letters Patent is:

1. A railway crossing, the rails of which present grooves at their intersections for the passage of wheel flanges, and present, in the tread of each crossing rail, at the far side of a groove, a surface elevated above the tread surface at the near side of the groove, there being inclines at said far sides of the grooves, leading from the said grooves to said elevated surfaces and adapted to receive the contact of a wheel tread before the tread leaves the rail surfaces at the near sides of the grooves. 50

2. A railway crossing, the rails of which present grooves at their intersections for the passage of wheel flanges, and present, in the tread of each crossing rail, at the far side of a groove, a surface elevated above the tread surface at the near side of the groove, there being inclines at said far sides of the grooves, leading from the said grooves to said elevated surfaces and adapted to receive the contact of a wheel tread before the tread leaves the rail surfaces at the near sides of the grooves, the adjacent elevated surfaces and the respective inclines of the crossing rails being at the same elevation at certain corners of the crossing, and, at other corners of the crossing the inclines and elevated surfaces of one rail being higher than the adjacent inclines and elevated surfaces. 65

LANCELOT RYAN. 70
